UNITED STATES PATENT OFFICE.

WILLIAM ANDREW WATTERSON, OF MACQUARIE RIVER, VIA EUCHAREENA, NEW SOUTH WALES, AUSTRALIA.

FAN FOR USE IN SPARK-ARRESTING AND SMOKE-CONSUMING DEVICES.

1,350,191.

Specification of Letters Patent. Patented Aug. 17, 1920.

Application filed August 5, 1919. Serial No. 315,501.

To all whom it may concern:

Be it known that I, WILLIAM ANDREW WATTERSON, a subject of the King of Great Britain, residing at Macquarie River, via 5 Euchareena, in the State of New South Wales, Australia, have invented an Improved Fan for Use in Spark-Arresting and Smoke-Consuming Devices, of which the following is a specification.

10 This invention relates to devices applied to smoke stacks of furnaces for drawing back the sparks and smoke and delivering same beneath the fire bars for destruction purposes and incidentally to improve the 15 draft and save fuel and labor.

15 The invention is particularly applicable to spark arresters wherein a steam jet projected across the smoke stack draws the smoke and sparks into a pipe leading beneath the fire bars of the furnace, said pipe 20 having a fan rotated by the current passing therethrough.

According to this invention the suction of 25 smoke is improved by means of a fan of special construction driven mechanically.

A practical illustration of the fan is depicted in the accompanying drawings whereof—

Figure 1 is an elevation of the fan;

30 Fig. 2 a vertical section of the fan cylinder and

Fig. 3 a section of one of the fan blades.

Fig. 4 is an enlarged cross section of one of the air inlets and its control shutter.

35 According to these drawings the fan comprises a cylindrical flanged casing 1 and a spindle 2 on which is a hub 3 carrying radial arms 4 bent at their outer ends to each of which is fixed a fan blade 5 curved as 40 shown in Fig. 3, and set tangentially as illustrated in Fig. 2, said blades being braced together by wires 6 to hold said blades in position relative to the periphery of the casing.

45 The spindle is journaled at each end in bearings 7 which are kept air tight by stuffing boxes 8 and at one end the spindle has means for rotating same such as a pulley 9 adapted to be rotated by a belt.

50 The suction pipe 10 through which the smoke, gases and sparks are drawn from

the stack is at the inlet side of the fan connected with a junction piece consisting of two branches 11, 12 the lower ends of which are cast with flared mouths 13 provided 55 with flanges 14 which are bolted to the flanges 15 at the ends of the casing, said flared mouths connecting with the end inlet openings of the fan casing.

The lower portion of each flared mouth 60 13 is formed with an air delivery port 16 (Figs. 1 and 4) controlled by a curved slide shutter 17 or the like, the edges of which engage in guides 13' on the bottom of the flared mouth 13, the object being to either 65 ease the suction from the stack or to increase the draft in the delivery pipe 18 connected to the fan casing and leading to the furnace.

The fan casing adjacent the delivery pipe 70 18 is formed with an outwardly bulging enlargement or recess 19 to accelerate the exit of the smoke into said delivery pipe.

I claim:—

1. A fan for spark arresting and smoke 75 consuming devices of the kind specified, consisting of a cylindrical casing, a mechanically operated spindle extending therethrough and upon which are fixed rotary fan blades, a discharge pipe from the casing, a junction pipe connected at one end with the suction pipe and formed at the other end with branches connected with the ends of the casing, the mouths of said branches being flared and provided with 80 controllable air inlets.

2. A fan for spark arresting and smoke consuming devices of the kind specified, consisting of a cylindrical casing, a mechanically operated spindle extending therethrough and upon which are fixed rotary fan blades, a discharge pipe from the casing 90 formed with an outwardly bulging recess, a junction pipe connected at one end with the suction pipe and formed at the other end 95 with branches connected with the ends of the casing, the mouths of said branches being flared and provided with controllable air inlets.

3. A fan for spark arresting and smoke 100 consuming devices of the kind specified, consisting of a cylindrical casing, a mechani-

cally operated spindle extending there-
through provided with a boss having radial
bent arms carrying curved fan blades set
tangentially and braced together by wires,
5 a discharge pipe from the casing formed
with an outwardly bulging recess, a junction
pipe connected at one end with the suc-

tion pipe and formed at the other end with
branches connected with the ends of the
casing, the mouths of said branches being 10
flared and provided with controllable air
inlets.

Dated this eleventh day of June, 1919.

WILLIAM ANDREW WATTERSON.
